UNITED STATES PATENT OFFICE.

PATRICK YORKE, OF WASHINGTON, PENNSYLVANIA.

STRUCTURAL-STEEL DERRICK.

1,306,783.

Specification of Letters Patent. Patented June 17, 1919.

Application filed September 28, 1918. Serial No. 258,049.

To all whom it may concern:

Be it known that I, PATRICK YORKE, a citizen of the United States, residing at Washington, in the county of Washington and State of Pennsylvania, have invented 5 certain new and useful Improvements in Structural-Steel Derricks, of which the following is a specification, reference being had to the accompanying drawings.

10 This invention relates to improvements in structural steel derricks, for use in drilling oil, gas, salt, and Artesian wells, although equally applicable for mining shafts, hoists, and other towers generally, and it has 15 for its primary object an improved structure of this character, the parts of which are so formed and arranged that they may be quickly assembled and disassembled without putting in or taking out a bolt.

20 To those familiar with the art to which this invention appertains, it is well known that in drilling gas wells for example, it is unnecessary to leave the derrick permanently erected over the well after it has once been 25 drilled, and consequently it is a desideratum to provide a structure that can be erected and dismantled at a minimum of cost and quickly, and with comparatively little labor; hence my invention aims, in one of its aspects, to attain this result and to provide an 30 improved derrick or similar structure which will possess to a maximum degree the susceptibility of being erected and dismantled expeditiously, and without the use of special 35 tools and with very little labor.

With these and other objects in view, as will more fully appear as the description proceeds, the invention consists in certain constructions, arrangements, and combinations 40 of the parts that I shall hereinafter more fully describe and claim.

For a full understanding of the invention, reference is to be had to the following description and accompanying drawing, 45 wherein—

Figure 1 is a side elevation of a portion of a derrick embodying my improvements.

Fig. 2 is an enlarged fragmentary view thereof.

Fig. 3 is a vertical longitudinal section taken approximately on the line 3—3 of Fig. 2.

Fig. 4 is a horizontal sectional view, the section being taken substantially on the line 55 4—4 of Fig. 2, and

Fig. 5 is a detail perspective view of one

of the bolts employed to securely, but detachably, connect the parts together as will be hereinafter more specifically described.

Corresponding and like parts are referred to in the following description and designated in all of the views of the accompanying drawing by like reference characters.

In describing the invention in detail it is to be borne in mind that the embodiment of the invention illustrated in the accompanying drawing, is for the purposes of illustration only, and hence only the vertically disposed portion of a well drilling derrick or similar structure is shown, the drilling rig being purposely omitted as unnecessary to a full understanding of the present improvements.

In the drawing, the numeral 1 designates the base of the derrick, said base being of any desired construction, material, or design, 2 designates the upwardly converging legs as a whole, 3 the girts which extend horizontally from one leg to another, and 4 the leg braces, which are preferably arranged to extend obliquely and in intersecting relation with each other, as clearly shown. Preferably the legs, girts and braces are of angle metal.

The legs 2 are formed of sections of any desired length, each section being designated 5. These sections 5 are disposed in longitudinal alignment with each other, with their ends abutting, and at the joints of the leg sections, splice bars 6 are disposed in overlapping relation to the adjoining sections, as clearly illustrated in the drawing. These splice bars 6 are also of angle metal and their sides or angularly disposed members are lapped upon the outer sides of the leg sections, and rivets 7 secure the splice bars to the subjacent sections, at the top, so that it will be understood that each leg section, as it goes out from the factory, has one of these splice bars permanently connected to it at its upper end and projecting beyond said end for the reception of the lower end of the next superjacent leg section when the leg sections are fitted together.

Each leg section 6 is formed in the lower edge of each of its angularly disposed members, with a bolt receiving slot 8, the inner or upper end of each slot being round and substantially three-fourths of a circle and the entrance end or portion of each slot being contracted relative to the inner end thereof and extending downward to the bot-

tom edge of the leg section in a substantially straight formation with approximately parallel side walls, as best illustrated in Fig. 3. In these slots 8 bolts 9 are received, one of 5 these bolts being illustrated in detail in Fig. 5.

I desire to call especial attention to the bolts 9 and the bolt receiving slots 8 as well as similar slots that are formed in the girts 10 and braces, for in these two features the present improvements mainly reside, and these two features together constitute primarily the means whereby the advantageous 15 results of this invention are secured. Each bolt 9 is formed with a threaded shank 10 for a nut 11, and with a head 12, and the shank 10 is flattened or formed in opposite sides with cut-out portions 13 next to the head 12, the head being formed on its outer face with a preferably diagonally disposed rib 14 which extends in a direction corresponding to the transversely flattened portion 13 of the shank whereby the workmen 20 may immediately tell the position of the partially round and flattened shank with respect to the bolt receiving slot in which it is accommodated by the corresponding position of the rib.

The girts 3 are formed in their ends with 25 bolt receiving slots 8' corresponding to the bolt receiving slots 8; and similarly the braces 4 are formed in their ends with corresponding slots 8'', bolts like those illustrated in Fig. 5 being received in the slots 8' and 30 8'' as well as in the slots 8, as clearly illustrated in the drawing, the only difference being a difference in the arrangement of the bolts. That is to say, in the slots 8 that are formed in the lower ends of the leg sections, 35 the bolts which extend through and are carried by the splice bars 6 are arranged with their ends innermost and their nuts outermost as indicated in Fig. 3, but the other bolts, that is, the bolts for the girts and leg 40 braces and which extend through and are carried by the leg sections and the overlapping portions of the splice bars, are disposed with their heads outermost and the nuts innermost.

From the foregoing description in connection with the accompanying drawing, it is believed that the operation of assembling the parts of a derrick or similar structure embodying the improvements of this invention will be apparent. As hereinbefore stated, the leg sections are shipped from the factory with the splice bars riveted thereto, and in the operation of assembling the parts, the leg sections are fitted one upon the other, 50 and the bolts 9 that are carried by the splice bars and never necessarily detached therefrom, are inserted in the straight contracted entrance portions of the slots 8 and then given a quarter turn in the three-quarter 55 circle upper ends of said slots, which mani-

festly prevents any detachment of the parts until the bolts are subsequently turned back again to a position where the side recesses 13 will be coincident with the straight walls 70 of the slots.

In a similar manner, the girts and braces are fitted over and upon the shanks of the bolts that are designed for them, and finally, when the bolts are turned to their proper locking positions, their nuts 11 are tightened 75 up, but whether the nuts are tightened up or not, it is manifest that once the parts are assembled and the bolts properly turned, the parts will be held together as against accidental detachment; and this is, manifestly, a 80 most important feature for if, for example, some of the tackle used in hoisting the parts should catch any parts already assembled, the parts thus caught or entangled might become entirely detached and fall or otherwise 85 cause damage to the structure and accident to the workmen and others were it not for the fact that the formation of these bolts and the correlated formation of the slots that receive them, make this impossible even 90 when the nuts are not tight. This is especially important because, in the erection of these derricks, it is customary to first assemble the parts with the bolts loosely held therein whereupon the rigger finally 95 tightens up the nuts after all the parts have been assembled and the nuts are not tightened up on each bolt as the work progresses.

While the accompanying drawing illustrates what I believe to be the preferred embodiment of my invention, it is to be understood that the invention is not limited thereto but that various changes may be made in the construction, arrangements and proportions of the parts without departing 100 from the scope of the invention as claimed.

I claim:

1. In a structure of the character described, parts adapted to be secured together and capable of detachment, one of said parts being adapted to carry a bolt and the other being formed with a bolt receiving slot extending from the edge of said part and having a round inner portion and a relatively contracted entrance portion, the bolt having 115 its shank rotatably mounted in the part which carries it, and said shank being formed with a flattened portion adapted to snugly fit in and pass through the contracted entrance portion of the slot and to be turned 120 in the inner end thereof whereby to prevent the accidental detachment of the parts.

2. In a structure of the character described, parts adapted to be secured together and capable of being detached, one of said parts being adapted to carry a bolt and the other being formed with a bolt receiving slot having a relatively large inner portion and a relatively contracted entrance portion extending from the edge of said part, the bolt 125

laving its shank rotatably mounted on the part which carries it and said shank being formed with a flattened portion adapted to snugly fit in the entrance portion of said slot and to be turned in the inner end thereof whereby to prevent the accidental detachment of the parts, the bolt being further formed with a head and the head being provided on its outer face with a rib which ex-

tends in a direction corresponding to the longer axis of the flattened portion of the bolt, for the purpose specified.

In testimony whereof I hereunto affix my signature in the presence of two witnesses.

PATRICK YORKE.
